Inventor:
Henry G. Saal

By G. L. Gray Atty.

UNITED STATES PATENT OFFICE.

HENRY G. SAAL, OF CHICAGO, ILLINOIS.

TELEPHONE RECEIVER.

Application filed March 20, 1925, Serial No. 17,081.

To all whom it may concern:

Be it known that I, HENRY G. SAAL, a citizen of the United States, residing at Chicago, in the county of Cook and the State of Illinois, have invented a certain new and useful Improvement in Telephone Receivers, of which the following is a full, clear, concise, and exact description.

My invention relates to telephone receivers employing polarized electromagnets whose armatures are connected with the receiver diaphragms by means of links which serve to transmit vibrations to the diaphragms instead of the diaphragms being directly subject to the action of the receiver magnets.

In carrying out my invention, the diaphragm of such a receiver is made of any suitable resilient sheet material, such as mica, bakelite or a suitable metal, and this diaphragm is tensioned to resist deflection from its normal plane in either direction. A link connects the diaphragm with the receiver armature in a manner to maintain a fixed distance between the portions of the armature and diaphragm connected thereby, whereby the diaphragm may position the armature centrally between the magnet poles and resist the movement of the armature from and restore the armature to its central position.

I employ a resilient coupling between the link and diaphragm which prevents grating noise and preserves, unimpaired, the mechanical union between these parts.

The invention will be more fully explained in connection with the accompanying drawing in which Fig. 1 is a sectional view of a watch case receiver made in accordance with the preferred embodiment of the invention, a portion of the body of the receiver casing being broken away; Fig. 2 is a view of the receiver on line 2-2 of Fig. 1, with parts removed and broken away; Fig. 3 is a view of the receiver on line 3-3 of Fig. 1, with parts broken away; and Fig. 4 is a view, in elevation, of the receiver minus the casing and diaphragm.

Like parts are indicated by similar characters of reference throughout the different figures.

The cup or body portion 1 of the watch case receiver casing is externally threaded at its rim to receive the casing cap 2 screwed thereon and having a central sound convey-

ing passage 3, here shown as being interiorly threaded for connection with a sound amplifying horn. A rigid cup 4 has its circular outsetting rim 5 clamped between the threaded end of the casing body and an annular ridge 6 formed upon the interior of the cap 2. The diaphragm 7, composed of mica, bakelite, or other suitable resilient sheet material, is interposed and clamped between the ridge and the annular rim of the cup, this rim constituting a seat for the diaphragm. The diaphragm is tensioned to resist deflection from its normal plane in either direction. A rivet 8 passes through a central portion of the diaphragm and has flanges 9 and 10, one upon each side of the diaphragm. The flange 9 is integrally formed with the body of the rivet and the flange 10 is secured in place by staking the rivet body as indicated at 11. Cushion washers 12 and 13 are employed, one being clamped between each rivet flange and the adjacent face of the diaphragm. A link 14 is screwed, at one end, into said rivet and is further secured thereto by a drop of solder 15 upon the outer ends of the link and rivet. This link is connected at its other end to one end of the armature 16, which is centrally pivoted upon the stirrup 17, between the U shaped polar extensions 18 provided upon the permanent magnet 19 and surrounded by the receiver winding 20. The connection of the link and armature is desirably effected by means of the hook 14' upon the link passing through the angular end 16' of the armature, a drop of solder 14' further holding the armature and link together. The link serves to maintain a fixed distance between the parts of the armature and diaphragm connected thereby, whereby the diaphragm will resist the movement of the armature from its middle position and will restore it thereto. The cushions or flexible coupling 9, 10 prevent grating noise between the link and diaphragm as well as prevent impairment of the mechanical union between these parts.

It is obvious that changes may be made without departing from the spirit of my invention.

Having thus described my invention I claim as new and desire to secure by Letters Patent the following:—

1. A telephone receiver including a polarized electromagnet having an armature; an

- annular diaphragm seat; a diaphragm of resilient sheet material secured at its periphery upon said seat and tensioned to resist deflection from its normal plane in either direction; a rivet passing through a central portion of the diaphragm and having a flange upon each side of the diaphragm; a cushion washer clamped between each rivet flange and the adjacent face of the diaphragm; and a link secured, at one end, into said rivet and connected at its other end to said armature, the link and rivet serving to maintain a fixed distance between the parts of the armature and diaphragm connected thereby. 3. A telephone receiver including a polarized electromagnet having an armature; an annular diaphragm seat; a diaphragm of resilient sheet material secured at its periphery upon said seat and tensioned to resist deflection from its normal plane in either direction; a link connected at one end with said armature; and a resilient coupling between the other end of the link and a central portion of the diaphragm, the link and coupling serving to maintain a fixed distance between the parts of the armature and diaphragm connected thereby.
2. A telephone receiver including a polarized electromagnet having an armature; an annular diaphragm seat; a diaphragm of resilient sheet material secured at its periphery upon said seat and tensioned to resist deflection from its normal plane in either direction; a rivet passing through a central portion of the diaphragm and having a flange upon each side of the dia-
- phragm; a cushion washer clamped between each rivet flange and the adjacent face of the diaphragm; and a link secured, at one end, into said rivet and connected at its other end to said armature, the link and rivet serving to maintain a fixed distance between the parts of the armature and diaphragm connected thereby. 3. A telephone receiver including a polarized electromagnet having an armature; an annular diaphragm seat; a diaphragm of resilient sheet material secured at its periphery upon said seat and tensioned to resist deflection from its normal plane in either direction; a link connected at one end with said armature; and a resilient coupling between the other end of the link and a central portion of the diaphragm, the link and coupling serving to maintain a fixed distance between the parts of the armature and diaphragm connected thereby.
- In witness whereof, I hereunto subscribe my name.

HENRY G. SAAL.
